(Cl. D86—10)

To all whom it may concern:

Be it known that I, Victor Silson, a citizen of the United States of America, residing in New York, county of New York, and State of New York, have invented a new, original, and ornamental Design for a Combined Lipstick and Brush Applicator Container, of which the following is a specification, reference being had to the accompanying drawing, forming part thereof.

Fig. 1 is a perspective view of a combined lip-

stick and brush applicator container showing my new design.

Fig. 2 is a perspective view thereof in exploded position.

I claim:

The ornamental design for a combined lipstick and brush applicator container, substantially as shown.

VICTOR SILSON.
